UNITED STATES PATENT OFFICE.

WILLIAM COOPER, OF DENVER, COLORADO.

COIN-SLOT MECHANISM.

1,167,744.

Specification of Letters Patent. Patented Jan. 11, 1916.

Application filed October 28, 1915. Serial No. 58,823.

To all whom it may concern:

Be it known that I, WILLIAM COOPER, a citizen of the United States, and residing in the city of Denver, in the county of Denver and State of Colorado, have invented or discovered new and useful Improvements in Coin-Slot Mechanism, of which the following is a specification.

My invention consists in new and useful improvements in coin slot mechanisms for pay-station telephones, coin-operated vending machines, and similar devices.

The object in view is the prevention of fraud by the use of coins not of the proper denomination or of a wire or other object to operate the mechanism. This object I accomplish by a new and improved coin slot mechanism, with transparent sides, wherein the coin is inserted into the top of the slot and depressed by means of a spring controlled plunger to spread a pair of spring controlled arms which hold in the slot the coin last previously introduced, permitting the last named coin to drop out of the lower end of the slot and the second coin to take its place in the slot.

Novel features of construction and arrangement of parts will appear from the following description.

In the accompanying drawings, Figure 1 is a side elevation showing a plurality of coin slot mechanisms mounted on the top of a coin operated or controlled device, such as a telephone box; Fig. 2 is an enlarged inside face view of the front plate of one of the coin slot mechanisms; Fig. 3 is an edge view of one of said mechanisms, and Fig. 4 is an inside face view of the back plate.

The following is a detailed description of the drawings.

A represents the top plate or portion of the device or machine upon which my improved coin slot mechanisms are mounted, and which is provided with a series of vertical openings or slots, α , through which the coins, released from said mechanisms, drop down into the machine. Any automatic bell ringing or product discharging mechanism, actuated by the dropping of the coin through the slot α , may be provided, but, as the same is no part of the present invention, it has not been shown.

B, B', B² and B³ represent a plurality of coin slot mechanisms, mounted on plate A and adapted to receive coins of various denominations. Thus in the case of a pay

telephone, the charges for calls of varying distances are different, so that mechanisms adapted to receive coins of different denominations are required. In the case of merchandise vending machines the value of the coins used is generally the same, so that but one coin mechanism, adapted to receive a penny or a nickel, is usually required.

The coin slot mechanism is composed of the front plate 1, the back plate 2, detachably secured thereto, as by screws 3, the spring retaining arms 4 and the plunger 5. The inner face of the front plate 1 is recessed to form a vertical coin slot 6 extending down to the bottom of said plate to the slot α in the plate A, the upper end of said slot extending at a downward angle from the side of plate 1, as at 7. A semi-cylindrical plunger seat 8 extends vertically to the top of plate 1 from the slot 6.

9 are the spring arm seats in the inside face of the plate 1, at either side of the slot 6 and communicating therewith at their tops and bottoms, as shown.

The spring detaining arms 4 are pivoted at their extreme tops to the plate 1 as by screw bolts 10, and are provided with inwardly extending upper and lower projections 4^a and 4^b, respectively.

11 are springs bearing against the outer faces of said arms 4 and normally holding the upper and lower ends of said arms extended into said slots 6. It is evident that a force tending to separate the upper ends 90 of said arms would also have a like effect on the lower ends thereof. While the lower ends of said arms preferably intersect substantially the entire width of the slot 6, the upper ends of said arms project but a short 95 distance into said slot from either side, as shown.

The back plate 2, which when in place closes the front face of the slots 6 and 7 and seat 8, is provided with a semi-cylindrical groove 12 which completes with the bore 8 the seat for the plunger 5. To provide sufficient metal to form the outer wall of groove 12, I may thicken the plate 2, as at 13.

The plunger 5 is cut away or flattened on its front face, as at 14, ending in shoulders 15, to receive the end of the screw 16 extending through a threaded hole in plate 2, thereby limiting the vertical movement of the plunger and preventing its accidental 110 escape from its seat. A helical spring 17 is coiled above the plunger between its head 18

and the top of the plates 1 and 2 to normally hold the plunger elevated out of the slot 6.

Above the lower ends 4^b of the arms 4, the sides of the slot 6 in the plates 1 and 2 are 5 cut away and glass panes 19 are set in, so that a coin resting on the lower ends of said arms is in plain view from without the mechanism.

20 are depressions in the inner face of 10 plate 2 to give clearance to the heads of the screws 10.

The lower ends of the plates 1 and 2 are provided with horizontal flanges 21 and 22, respectively, which are secured to the top 15 plate A or other base, as by screws 23. Where there are a plurality of coin slot mechanisms, as in Fig. 1, the base flanges 21 of all plates 1 are in one piece or integral as is likewise the case of the flanges 22 of the 20 plate 2. Thus the plates 1 may all be installed at one time, and then the plates 2; and the connecting screws 3 inserted to bind said plates 1 and 2 together.

The operation of the mechanism is as follows. The coin first inserted, marked C 25 falls down the inclined slot 7 and rests on the top ends 4^a of the spring arms 4. The plunger is then depressed forcing the arms 4 apart and permitting the coin to assume 30 the position shown in Fig. 2, resting on the ends 4^b of the arms 4. Said coin is in full view through the glass panes 19. When the device is to be put to use, the slot mechanism or mechanisms are loaded with the proper 35 coin resting on the lower ends 4^b of the arms 4. It is evident that a wire or other article inserted down into the slot 6 through the inclined slot 7 would not be able to engage the ends 4^b of both arms 4 to spread the 40 lower ends of the arms and permit the coin C to drop into the machine but a second coin D, of the proper denomination must be slipped down the slot 7 into the slot 6 and be forced downwardly by the plunger to 45 force the coin C down through the bottom of the slot mechanism. The pressure of a wire or other article on the top edge of the lower coin C would not spread the lower

ends 4^b of the arms 4 to permit said coin C to drop. The inclined angle of slot 7 renders the insertion of a wire difficult. Thus after my coin slot mechanism has been operated by the introduction of a coin and the depression of the plunger, the coin so introduced is in full view and cannot be forced down out of the bottom of the coin slot mechanism except by the introduction of a second coin and the depression of the plunger.

What I desire to claim is:—

1. A coin slot mechanism consisting of a casing provided with a coin slot; a pair of spring actuated pivoted retaining arms having inwardly extending top and bottom ends intersecting the said slot, the coin 65 first introduced being held in the lower portion of said coin slot by the lower ends of said arms and the coin last introduced resting upon the upper ends of said arms in the upper portion of said slot, and a spring controlled plunger adapted to be forced down against said second coin whereby said arms are spread apart to permit the first coin to drop down out of said coin slot and the second coin to assume the previous position of 70 said first coin, for the purpose described.

2. A coin slot mechanism consisting of a casing provided with a vertical coin slot having an inclined upper mouth; a pair of spring actuated pivoted retaining arms having inwardly extending top and bottom ends intersecting said slot, the coin first introduced being held in the lower portion of said coin slot by the lower ends of said arms and the coin last introduced resting upon the 85 upper ends of said arms in the upper portion of said slot, and a spring controlled plunger adapted to be forced down against said second coin whereby said arms are spread apart to permit the first coin to drop down out of 90 said coin slot and the second coin to assume the previous position of said first coin, for the purpose described.

Signed at Denver, Colorado, this 20th day of October, 1915.

WILLIAM COOPER.
